(57) **CLAIM**

The ornamental design for a pet remote, as shown and described.

DESCRIPTION

FIG. 1 is a right front perspective view of a pet remote showing my new design;

FIG. 2 is a right side elevational view, the left side being substantially a mirror image thereof;

FIG. 3 is a bottom plan view thereof;

FIG. 4 is a top plan view thereof;

FIG. 5 is a front elevational view thereof; and,

FIG. 6 is a rear elevational view thereof.

The structural features depicted by broken lines in the drawing have been provided for the purpose of illustrating portions of the pet remote that form no part of the claimed design.

The thin solid lines illustrate the contour of the claimed design and are not a surface pattern.
